UNITED STATES PATENT OFFICE

94,128

DESIGN FOR A MONUMENT

Benjamin Edwin Goldberg, Dallas, Tex.

Application July 14, 1934, Serial No. 52,582

Term of patent 3½ years

To all whom it may concern:

Be it known that I, Benjamin Edwin Goldberg, a citizen of the United States, residing at Dallas, county of Dallas and State of Texas, have invented a new, original, and ornamental Design for a Monument, of which the following is a specification, reference being had to the accompanying drawing, forming part thereof.

The figure is a perspective view of a monument, showing my new design.

I claim:

The ornamental design for a monument as shown.

BENJAMIN EDWIN GOLDBERG.
